RACKET BOW CAUL

Horace W. Hall, Newton, Mass.

Application June 17, 1931. Serial No. 544,970

9 Claims. (Cl. 144—259)

This invention relates to a racket caul and more particularly to an assembly of cauls to form a racket bow.

By the term racket bow I include the head or curved portion and the straight handle portion.

In the formation of a racket block composed of a plurality of wood laminations from which a number of rackets, usually about twelve, are cut out, the shape, sectioning and arrangement of the cauls by which the wood laminations are bent and held to bow shape is extremely important. The size of the block and the fact that the glue between the laminations sometimes runs out and gets between the laminations and the cauls makes the separation of the racket block from the inside caul a serious problem.

One object of my invention is to provide an assembly of cauls by means of which a plurality of wood laminations in block size could readily be bent and held to a racket bow shape. Another more important object was to make said assembly of cauls readily separable from the racket block after it had assumed bow shape. Still another object has been to make said cauls so simple that the bending and removal of said block may be expeditiously accomplished by relatively unskilled labor.

The foregoing and other objects which will appear as the nature of the invention is better understood, may be accomplished by a construction, combination and operative arrangement of parts such as is disclosed by the drawings. The nature of the invention is such as to render it susceptible to various changes and modifications and, therefore, I am not to be limited to the construction disclosed by the drawings; but am entitled to all such changes therefrom as fall within the scope of my claims.

40 In the drawings:

Figure 1 is a plan view showing a block bent into racket shape, and so held by my cauls under pressure.

Figure 2 is a cross-section on the line 2—2 of Figure 1 more fully illustrating the shape of the cauls and the means of applying pressure.

Figure 3 is a perspective view of the inside caul.

Figure 4 is a perspective view of a racket block with closed throat sections united thereto, the arrows indicating the pressure points on said block during the bending operation.

Figure 5 is a perspective view of a racket block with abbreviated or open throat sections united thereto, the lower insert showing one of a pair of cauls for forming the open throat portions.

As illustrated a racket block 12 is composed of a plurality of wood laminations glued together from which a number of rackets are sawed, said laminations being bent around an

inside head caul 13 and a handle caul later described, to thereby form a racket bow. Said inside head caul 13 is cored out and made as light in weight as practical, the hole 14 extending through it, although preferably much smaller at each end than in the middle (see Figure 2 of the drawings), larger and thicker end portions being desired in order to withstand the pressure at these points. At the bottom of said inside caul 13 a recess 15 is cut therein for purposes of alinement, and a handle caul 17 of about $\frac{1}{4}$ " thickness fits into said recess 15 and extends through the handle of the bow so that it may be held, for instance in a slot in a holding block. It will be noted in Figure 1 of the drawings, which is a view looking downwardly on the block 12, that said inside head caul 13 has a very slightly raised portion 18 on its outside surface which establishes a center line or mark inside the racket bow head that is a useful guide for later operations. Said recess 15 for the handle caul 17 is in alinement with said raised portion 18.

The outside caul is preferably composed of a number of parts there being shown a top section 20, two side sections 21, two throat sections 22 and two handle sections 23. Said throat sections 22 commence at the beginning of the throat curve in the bow, and pressure is applied at this important point to directly overcome the tendency of the laminations to spread apart in this reversal of the curve. All the cauls are preferably made of metal, such as cast iron.

Upon bending the wood laminations around said inside caul 13, and said handle caul 17, gluing the two wooden side sections 24 of the throat to the bow block 12 as previously disclosed in my application filed December 27, 1926, Serial No. 157,059, now Patent No. 1,831,350 issued November 10, 1931, and placing said outside caul sections in position, this assembly must be tightly held together until the glue has set. To accomplish this a number of rods 25 extend through said inside caul 13 and said block 12, those rods having pins 26 on their ends to hold said rods from slipping through one end of said inner caul 13, being given the numeral 25a. Metal straps 27, which are U-shaped, extend around said rods 25 and 25a and are fastened at their open ends to long bars 28 by pins 29 which extend through said straps 27 and said long bars 28, being held in place by cotter pins 30. Set screws 32 extending through a threaded interior of said long bars 28 are adapted to be screwed against bosses 33 formed at various pressure points on the outside caul sections, the tightening of which set screws 32 forces said outside caul sections toward the racket block 12 and also draws the inside head caul 13 towards said block, thereby pressing and holding the wood laminations, which have glue on their surfaces, very tightly together. The two

120

115

110

105

100

handle portions of the racket bow are similarly drawn towards each other and tightly held with said handle caul 17 between them.

Loosely mounted in said long bars 28 are dowel pins 33a which press fit into said outside caul sections 20, 21 and 22, to prevent separation of said long bars 28 and said caul sections 20, 21 and 22 when the straps 27 are released. As shown in Figure 2 of the drawings said lower strap 27 serves as a hinge thereby permitting said long bars 28 and outside caul sections 20, 21 and 22 to drop to the position shown in broken lines in said Figure 2.

At the lower ends of said rods 25a which extend through a table 35, nuts 36 are secured on the threaded ends of said rods 25a, thereby fastening said inside caul 13 to said table 35 by means of said rods 25a, as the pins 26 at the upper ends of said rods 25a keep them from slipping through said inside caul 13. Said table 35 is provided with a metal top or covering 37, and interposed between said top 37 and inside caul 13 is a spacer block 38 to prevent binding of the lower straps 27 against said table top 37 and bottom surface of said inside head caul 13. Said table 35 is firmly secured to the floor by a standard 39 shown broken away in said Figure 2.

In forming a racket block to bow shape so it will have an open throat a metal caul 40 is inserted below each wooden throat section 24, which throat sections are in this instance abbreviated as shown in Figure 5 of the drawings, said metal caul thereby forming openings 41 on each side of said handle caul 17, which openings are commonly referred to as an open throat.

Upon removal of the cauls from the racket block, a wooden strip 42 is inserted in the center and glued to the handle portion of the racket bow in place of the handle caul 17.

The removal of the racket block 12 from the cauls is effected by first removing the outside cauls 20, 21, 22 and 23, then the handle caul 17, the center space left thereby in the handle portion provides an expansion space eliminating any internal strains which may have been set up at this point, preventing thereby any glue fractures in the process of removing the block 12 from the inside caul 13. Said block 12 is next removed by forcing the hand in the center space at the base of the handle portions slightly spreading the same, which is sufficient to release the head portion of the bow from the inside caul 13. The block 12 is then lifted with the other hand away from said caul. It will be noted that all this is accomplished by short, simple operations, and without using the collapsible inside caul formerly necessary.

What I claim is:

1. An assembly of cauls for a racket bow comprising a plurality of outside caul sections, two of said sections terminating at the curve substantially opposite the top throat portion of said racket bow, an inside head caul and a handle caul adapted to extend from said inside caul into the handle of said racket bow, and means adapted to hold said cauls to said racket bow.

2. An assembly of cauls for a racket bow comprising a plurality of outside caul sections, an inside head caul of the shape of the head of said racket bow having a raised portion on the

top outside surface at the center of said inside caul and having a recess in the bottom of said inside caul in alignment with said raised portion, and a handle caul adapted to fit into said recess and extend therefrom into the handle of said racket bow, and means adapted to hold said cauls to said racket bow.

3. An assembly of cauls for a racket bow comprising outside cauls, a single unit inside caul having the shape of the head of said racket bow, a separate caul adapted to extend from a point in contact with said inside caul into the handle of said racket bow, and means adapted to hold said cauls to said racket bow.

4. An assembly of cauls for a racket bow block comprising an outside caul, an inside head caul having a raised portion on the outside surface at the center thereof and having a recess in the bottom in alignment with said raised portion, a handle caul adapted to fit into said recess and extend therefrom into the handle portion of said racket bow block, and means to hold said cauls to said racket bow block.

5. An assembly of cauls for a racket bow block comprising seven outer caul sections, one of said sections being at the top, two at the sides, two at the throat and two at the handle of said block, an inside caul, a separate handle caul extending from said inside caul into the handle of said bow block, and means adapted to hold said cauls to said racket bow block.

6. An assembly of cauls for a racket bow comprising a plurality of outside sections, an inside head caul, a separate handle caul extending into the handle of said racket bow, and means adapted to hold said cauls to said racket bow.

7. An assembly of cauls for a racket bow block comprising a plurality of outside sections, an inside head caul, a separate handle caul extending from said inside caul through the handle of said racket bow, said inside caul having provision to receive a portion of said handle caul, and means adapted to hold said cauls to said racket bow block.

8. An assembly of cauls for a racket bow comprising an outer caul adapted to extend across the top of the bow head, two outer cauls adapted to extend from said first-mentioned caul to the throat portion of said racket bow, two outer cauls adapted to extend from said second-men- 125 tioned cauls to a portion of the handle of said racket bow, two outer cauls adapted to extend from said third-mentioned cauls down the handle of said racket bow, an inside head caul having a recess therein, and a separate handle caul 130 adapted to fit into said recess and extend therefrom into the handle of said racket bow, and means to hold said cauls to said racket bow.

9. In combination, an assembly of cauls and a racket bow block held in bow shape by said cauls, comprising a plurality of outside caul sections, an inside head caul around which the head of said racket block is bent, a separate handle caul extending from said inside caul into the handle portion of said block, two throat side 140 pieces glued to said bow block below said inside caul and on each side of said handle caul, two open throat cauls below said side pieces, and means to firmly hold said block to said cauls.

HORACE W. HALL. 145
